(57) **CLAIM**

The ornamental design for a baby bib, as shown and described.

DESCRIPTION

FIG. 1 is a top perspective view of a baby bib.

FIG. 2 is a front elevational view thereof;

FIG. 3 is a rear elevational view thereof;

FIG. 4 is a side elevational view thereof;

FIG. 5 is a right side perspective view thereof, shown in an open position;

FIG. 6 is a bottom perspective view thereof; and,

FIG. 7 is a left side perspective view thereof.

The broken lines shown in the drawings represent features of the baby bib that form no part of the claimed design.
